UNITED STATES PATENT OFFICE.

JOHN MITCHELL, OF PHILADELPHIA, PENNSYLVANIA.

CLOTHES-LINE HOOK.

1,067,748.

Specification of Letters Patent. Patented July 15, 1913.

Application filed March 21, 1913. Serial No. 755,990.

To all whom it may concern:

Be it known that I, JOHN MITCHELL, a citizen of the United States, residing at Philadelphia, in the county of Philadelphia and State of Pennsylvania, have invented 5 new and useful Improvements in Clothes-Line Hooks, of which the following is a specification.

This invention relates to clothes line 10 hooks; and it has for its object means for supporting the hook for longitudinal adjustment along the rail of the fence and means for facilitating the operation of removing the hook when desired.

15 Another object of the invention is the provision of a hook wherein its clamping engagement with the fence will be maximized under the weight of the articles suspended from the line.

20 With these and other objects in view, the invention consists of certain novel features of construction, combination and arrangement of parts, as will be hereinafter described and claimed.

25 In the accompanying drawings:—Figure 1 is a sectional perspective view of a portion of a fence structure, showing the application of the hook thereto; and Fig. 2 is a front view thereof.

30 The fence structure A conventionally illustrated herein includes a top rail B, which is extended beyond the vertical sides of the fence, as shown in Fig. 1. The line supporting member comprises a plate 1 which 35 rests against the upper surface of the rail B, and it is provided at one end with a vertically depending flange 2 which is disposed immediately along one of the vertical sides of the rail B and which terminates 40 in a retaining or clamping element 3 which extends at right angles to the plane of the flange 2 and which is constructed so as to permit of its engagement with the under surface of the rail B at one side of the 45 fence structure. At the opposite end the plate 1 is extended beyond the opposite vertical side of the rail B and provided with alined knuckles 4, which are spaced relatively for the reception therebetween of an

50 intermediate portion 5 of a line supporting hook 6. The portion 5 is extended laterally, as at 7, and then downwardly and inwardly in the form of a nose 8, which is pivotally connected at 9 with a clamping head 10. The portion 5 is pivotally connected in the knuckles 4 through the medium

of a pin 11, as shown. This construction is such that the tongue of the hook is connected with the portion 5 through an intermediate relatively long and heavy arm 12 whose 60 weight operates or acts normally to move the hook in one direction and thereby advance the head 10 in the direction of the adjacent vertical side of the rail B, causing the same to coöperate with the clamping 65 element 3 of the flange 2 and in this manner secure the device in operative position upon the fence structure.

It is evident that when a line is connected in any obvious well known manner with 70 the hook 6 its weight, and the weight of the articles hung from the line will advantageously contribute to the weight of the long arm 12 toward holding the head 10 in proper gripping contact with the rail B. 75 When desired, the hook may be rocked manually so as to permit the plate 1 to be shifted to any desired point in the length of the rail B. Then again it is stated that the hook may be adjusted so as to cause the 80 head 10 to be disposed slightly above the plane of the plate 1 and thereby permit the latter to be adjusted laterally over the upper surface of the rail B with a resultant disengagement of the retaining or clamping 85 portion 3 from the rail.

From the foregoing description, taken in connection with the accompanying drawings, the construction and operation of the invention will be readily understood without 90 requiring a more extended explanation.

Various changes in the form, proportion and the minor details of construction may be resorted to without departing from the principle or sacrificing any of the advantages of this invention, as claimed.

Having thus described my invention, what I claim is:—

1. A clothes line hook comprising a flat metal plate bent at one of its ends to provide a depending flange, an integral clamping extension lying at right angles to the plane of the flange, the opposite end of the plate having spaced alined loops, a hook pivoted between the loops and provided with a relatively long upper arm terminally overlying the plate and a lower lateral extension formed on the hook below its point of connection with the plate, and a flat clamping head pivotally connected with the 100 lower end of the hook.

2. A clothes line support for fence struc-

tures comprising a flat plate overlying the rail of the structure and having one of its ends bent angularly to provide a depending flange having a free portion underlying the top rail of the fence structure, the said plate having its opposite end extended beyond the adjacent longitudinal side of the rail of the fence structure and provided with aligned loops, a hook pivoted between the loops and provided with a relatively long and heavy upper arm curved through-

out its length and terminally overlying the plate, and a clamping head pivotally connected with the hook below the point of connection of the latter with said loops. 15

In testimony whereof I affix my signature in presence of two witnesses.

JOHN MITCHELL.
